UNITED STATES PATENT OFFICE.

EVERETT BARD, OF WATER VALLEY, KENTUCKY.

JAR-COVER CRIMPER.

Application filed August 31, 1922. Serial No. 585,458.

To all whom it may concern:

Be it known that I, EVERETT BARD, a citizen of the United States, residing at Water Valley, in the county of Graves and State 5 of Kentucky, have invented a new and useful Jar-Cover Crimper, of which the following is a specification.

This invention relates to an implement designed for use in bending the rubber engaging 10 flange of a fruit jar cover to cause the same to closely engage the jar rubber to exclude air.

Another object of the invention is to provide a device of this character which may 15 be easily moved around a jar cover to accomplish the purpose of the invention, novel means being provided for holding the implement to its work.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed, may be made within the scope of what is claimed, without departing from the spirit of the invention.

Referring to the drawing:

30 Figure 1 is a side elevational view disclosing a device constructed in accordance with the invention.

Figure 2 is a front elevational view of the same.

35 Figure 3 is a detail view of the crimping roller.

Referring to the drawing in detail, the device embodies a shank 5 which has one end thereof bifurcated as at 6, to support the 40 crimping roller 7.

This crimping roller is formed with a flange 8 and a crimping surface 9 adapted to be forced into engagement with the flange of a jar cover to bend the same into close en-

gagement with the rubber associated therewith. 45

Secured to the shank 5 is a supporting arm indicated at 10 which has a right angled portion 11 adapted to contact with the edge of the cover to which the same is applied, 50 and which in the present showing is indicated at 12 to hold the device to its work and permit the operator to force the roller into close engagement with the flange 13 of the cover. 55

The handle 14 is secured to the shank and enables the operator to properly grip the implement to accomplish the purpose of the invention.

In the use of the device, the implement is 60 positioned in a manner as shown by Figure 1 of the drawing, whereupon the operator places his hand over the cover and at the same time grips the supporting arm, while the other hand of the operator may be used 65 to press the roller into engagement with the flange of the cover.

What is claimed as new is:—

In a tool of the class described, a shank having a cut out portion formed at one end 70 thereof and having a handle formed at the opposite end thereof, a roller positioned within the cut out portion for contacting with the cover of a fruit jar, a supporting arm extending laterally from the shank and 75 at right angles with respect thereto, said supporting arm having a right angled extremity adapted to engage the cover under operation, and said supporting arm adapted to be gripped by one hand of the operator 80 to hold the tool to the cover.

In testimony that I claim the foregoing as my own, I have hereto affixed my signature in the presence of two witnesses.

EVERETT BARD.

Witnesses:

J. W. GATES,
H. W. STEPHENS.
